BOTTLE HOLDER AND CARRIER

George H. Hutaff, Jr., Wilmington, N. C.

Application July 1, 1941, Serial No. 400,674

2 Claims. (CL. 294—87)

My invention relates to new and useful improvements in bottle holders or carriers and has for its principal object the provision of a device of the character described which is adapted to hold a plurality of bottles so that they may be carried from place to place such as from the place of purchase to the home or to the place where the contents of the bottles are to be consumed. Likewise empty bottles may be carried to a store or other place of purchase where the bottles may be either redeemed or purchase made of another supply of filled bottles.

Another object of the invention consists in the provision of a holder or carrier including what might be termed a stationary member and a movable member, edges of the members being formed with cut-outs or notches to receive the necks of the bottles when the members are in normal positions so that a plurality of bottles may be supported and carried from place to place, the bottles being removable from the holder or carrier when the movable member is swung to what might be termed open position or to a position out of engagement with the bottle neck.

A further object of the invention resides in the provision of a bottle holder or carrier including a stationary member and a movable member adapted to be engaged with the neck or necks of a bottle or bottles for supporting the same to be carried from place to place, means being provided for holding the movable member in bottle-engaging position against accidental misplacement.

Still another object of the invention resides in the provision of a carrier or support for a plurality of individual bottle holders or carriers, the carrier or support for the individual holders or carriers being provided with means for positioning the individual holders or carriers and holding or locking the same against accidental displacement.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings:

Fig. 1 is a top plan of what might be termed a

holder or carrier for supporting six bottles in line.

Fig. 2 is a top plan of the holder or carrier shown in Fig. 1 with the movable member swung into open or bottle-receiving position.

Fig. 3 is a transverse vertical section on the line 3—3 of Fig. 1 looking in the direction of the arrows.

Fig. 4 is a transverse vertical section on the line 4—4 of Fig. 1 looking in the direction of the arrows.

Fig. 5 is a top plan of a modified form of my invention for holding parallel rows of bottles, three bottles being adapted to be supported in each row.

Fig. 6 is a top plan of the form of the invention shown in Fig. 5 with the movable members swung into open or bottle-receiving position.

Fig. 7 is an end view of Fig. 6.

Fig. 8 is a top plan of a support or carrier for a plurality of individual bottle holders or carriers of the construction shown in Figs. 1 to 4 inclusive, one of the individual holders or carriers being shown in position.

Fig. 9 is a transverse vertical section on the line 9—9 of Fig. 8 looking in the direction of the arrows.

Fig. 10 is a view similar to Fig. 8 showing a support or carrier for a plurality of individual bottle holders or carriers of the formation shown in Figs. 5 to 7 of the drawings, one of the individual holders or carriers being shown in position; and

Fig. 11 is a transverse vertical section on the line 11—11 of Fig. 10 looking in the direction of the arrows.

In the sale and purchase of bottled beverages it has been found desirable to provide a holder or carrier other than the well-known form of paper bag which has disadvantages so far as the holding and carrying of bottles is concerned. It is hard to stack the bottles in a paper bag in proper form for carrying and the bottles will rattle causing undesirable noise. At the same time bottles containing the beverage are very often taken out of the ice box or off of the ice and there is moisture on the outside of the bottles. If these wet bottles are placed in a paper bag the bag becomes damp and can be easily torn thereby dropping the bottles and causing the same to break. In my improved forms of carrier the desired number of bottles may be placed in the holder and carried from place to place. The bottles are properly spaced so that they do not contact and it makes no difference whether the

bottles are wet or not. Holders such as I have disclosed are of further advantage in that they are convenient for returning empty bottles to the store or other place of purchase. It has become the custom for dealers to require the customer to make a deposit on the bottles when purchasing. It is therefore to the advantage of the customer to return the empty bottles either to secure the refund of the deposit or to prevent the necessity of making a further deposit when a new purchase is being made. My improved forms of holders are of such a character that they may be retained by the purchaser or used over-and-over many times, thereby having advantage over holders or bottle carriers formed of destructible material such as pasteboard or the like.

In that form of holder or carrier such as is shown in Figs. 1 to 4 inclusive of the drawings six bottles are adapted to be supported in line, but I wish it understood that I do not limit the device for use with any particular number of bottles and it will be appreciated that the holder might be made of a length to hold and carry a lesser number of bottles, than disclosed in Figs. 1 and 2, or a greater number as may be found desirable. The holder and carrier, shown in Figs. 1 to 4 inclusive, includes what might be termed a stationary member 1, in the form of a strip, provided on its inner edge with a plurality of semi-circular notches or recesses 2 and on its outer edge having the curved portion 3 cooperating to provide a hand-engaging portion as will be later appreciated. Secured to the under surface of the strip 1, by means of the screws 4 or other suitable fastenings, are the longitudinally spaced cleats or strips 5 which project beyond the inner edge of the strip 1, as is quite clearly shown in Figs. 2 and 3 of the drawings.

Hingedly connected at 6, to the ends of the outermost strips or cleats 5, is what might be termed the movable member of the holder or carrier which is adapted when carrying bottles to be positioned as shown in Fig. 1 of the drawings or when receiving the bottles to be positioned as shown in Fig. 2. The position shown in Fig. 1 might be termed the normal position and the position shown in Fig. 2 the bottle-receiving position. This movable member is designated 7 and is provided on its normal inner edge with a plurality of semi-circular notches or recesses 8 adapted to cooperate with the notches or recesses 2 to provide circular openings for the reception of the bottle necks, as shown more particularly in Fig. 4 of the drawings, the bottle neck being indicated at 9. The normal outer edge of the strip or member 7 is curved as shown at 10, similar to the curved portion 3 of the strip 1, and when the strips or members are in their normal position, shown in Fig. 1 of the drawings, the said curved portions 3 and 10 present a hand-gripping portion whereby the bottle holder may be carried from place to place. I wish to lay particular stress on the fact that the cleats or strips 5 form means for hingedly connecting the movable member to the stationary member and also form a support for the movable member when the same is in bottle-holding or carrying position, shown in Fig. 1 of the drawings. The cleats or strips form a support for the movable member and prevent what might be termed any vertical movement of the movable member relative to the stationary member, such as would cause uneven grip around the bottle necks. To prevent any lateral spread or separation of the members 1 and 7 a metal strip 11 is secured to the upper surface of the movable member 7 by screws 12

or other suitable fastenings and the end of this strip is bent to form the angular portion 13. When the members 1 and 7 are in the bottle-carrying position, shown in Fig. 1 of the drawings, the strip 11 will extend over the upper surface of the strip or member 1 with the angular extension 13 extending parallel with the outer edge of the member or strip 1 and in frictional engagement therewith. For preventing accidental displacement or swinging of the strip or member 1 relative to the strip or member 7 I provide the rotatable button 14 secured to the strip or member 1 and adapted to be positioned, as shown more particularly in Fig. 1 of the drawings, with an end overlapping the upper surface of the strip or member 7. When it is desired to swing the strip or member 7 the button will be turned into the position shown in Fig. 2 to extend longitudinally of the strip or member 1.

While I have only shown the movable strip or member 7 hingedly connected to the outer or end cleats or strips 5, it can be appreciated that if desired hinged connection might be made with all of the cleats or strips or only with the intermediate cleats or strips. I want to again emphasize the fact that these cleats or strips form not only means for hingedly connecting the movable member to the stationary member, but act as a support for the movable member when it is in its bottle-carrying position shown in Figs. 1, 3 and 4 of the drawings. When the movable strip or member is swung into the open position, shown in Fig. 2, the necks of the bottles may be readily inserted between the strips or members 3 and positioned in the notches or recesses 2 of the strip or member 1. Then when the strip or member 7 is swung to overlie the cleats or strips 5 and to be supported thereby the recesses or notches 8 will cooperate with the recesses or notches 2 to provide circular openings through which the bottle necks are supported.

In Figs. 5, 6 and 7 of the drawings I have shown a slightly modified form of my holder or carrier for the support and carrying of six bottles in parallel rows of three bottles in each row. In this modified form of the invention the holder or carrier includes a stationary central member, shown at 15, and the movable members 16 and 17 positioned on opposite sides of the central stationary member as shown. The central stationary member 15 is formed on each longitudinal edge with the longitudinally spaced semi-circular notches or recesses 18 and each of the movable members 16 and 17 is formed in one longitudinal edge with the longitudinally spaced semi-circular recesses or notches 19 adapted to cooperate with the notches 18 when the members 16 and 17 are in bottle-carrying position to provide circular openings through which the necks of the bottles are received. The notches 19, of the strips 16 and 17, are formed in what might be termed the normal inner edges of the members or the edges which are in juxtaposition with the edges of the central stationary member 15 when in bottle-carrying position.

Secured to the under surface of the central stationary member 15, by the screws 20 or other suitable fastenings, are the transversely extending strips or cleats 21 which project beyond the longitudinal edges of the member 15, as is quite clearly shown more particularly in Figs. 6 and 7 of the drawings. As shown more particularly in Figs. 5 and 6 of the drawings these cleats or strips 21 are longitudinally spaced from one another and are positioned inwardly of the ends

of the member 15. The movable strips 16 and 17 are hingedly connected to opposite ends of the cleats or strips 21, as shown at 22, so that they may be readily swung to the desired positions. As in that form of the invention disclosed in Figs. 1 to 4 inclusive of the drawings the cleats or strips 21 form a support for the movable members 16 and 17 when they are swung into the positions shown in Fig. 5 of the drawings or what might be termed the closed bottle-carrying positions. To hold the members 16 and 17 in their bottle-carrying positions, against accidental displacement, I provide the buttons 23 which are rotatably connected to the member 15 and adapted to overlie the edges of the strips or members 16 and 17 as shown more particularly in Fig. 5 of the drawings. A handle 24 is secured to the central member 15, by means of the screws 25 or other suitable fastenings.

With the movable members positioned as shown in Figs. 6 and 7 of the drawings the necks of the bottles may be inserted between the central member 15 and movable members 16 and 17 and positioned in the notches or recesses 18. When the movable members 16 and 17 are swung into the closed or bottle-carrying positions shown in Fig. 5 of the drawings the notches or recesses 19 cooperate with the notches or recesses 18 to provide circular openings receiving and engaging the necks of the bottles.

It can be appreciated that at times it may be advantageous and desirable to support or carry a plurality of the individual bottle holders or carriers disclosed in Figs. 1 to 7 inclusive of the drawings. For this purpose I have provided the carrier shown in Figs. 8 and 9 in the form of a tray for supporting four of the individual holders or containers, shown in Figs. 1 to 4 inclusive of the drawings. In Figs. 10 and 11 of the drawings I have illustrated a support or carrier in the form of a tray to receive four of the individual holders or carriers shown in Figs. 5 to 7 inclusive of the drawings.

In that form of support or carrier shown in Figs. 8 and 9, a tray is provided including the bottom 26, longitudinally extending side flanges 27 and end flanges 28, the flanges 27 and 28 projecting upwardly from the bottom 26 and the end flanges having openings 29 to receive the fingers of the user whereby the tray may be carried from place to place. The bottom 26 is formed with the transversely spaced longitudinally extending openings 30 through which the bottles carried by the individual holders or carriers may extend, as shown more particularly in Fig. 9 of the drawings. Secured to the upper surface of the bottom 26, and extending longitudinally thereof between adjacent openings 30, are the strips 31. Individual holders or carriers may be positioned between the strips 31 and between the outermost strips and the side flanges 27, one of such individual holders or carriers being indicated at a and, as has been previously stated, they are of the formation disclosed in Figs. 1 to 4 inclusive of the drawings. Rotatably secured to the side flanges 27, as well as the longitudinally extending strips 31, are the buttons 32 which when in the positions shown overlie the upper surfaces of the individual holders or carriers. When it is desired to remove the individual holders or carriers from the tray the buttons may be rotated to be positioned longitudinally of the side flanges 27 and strips 31 so that

they will not overlie the individual holders or containers.

The form of carrier or tray shown in Figs. 10 and 11 of the drawings includes the bottom 33, upstanding side flanges 34 and upstanding end flanges 35 having openings similar to the openings 29 to receive the fingers of the user for carrying the tray from place to place. The bottom 33 is formed with four openings 36 arranged as shown and secured to the upper surface of the bottom 33 is the longitudinally extending strip 37 and transversely extending strips 38, these latter strips 38 being positioned between the strip 37 and upstanding side flanges 34, as is shown quite clearly in Fig. 10 of the drawings. The strips 37 and 38 divide the top into what might be termed four compartments, in each of which may be positioned an individual holder or carrier which I have designated at b and which are of the formation shown in Figs. 5 to 7 inclusive of the drawings. Pivotedly connected to the upper surfaces of the upstanding side flanges 34 and the strip 37 are the buttons 39 which are adapted to overlie the upper surface of the individual holders or containers and hold them in the tray against accidental displacement. When it is desired to remove the individual holders or containers the buttons may be rotated or swung so that they do not overlie the individual holders or containers.

In that form of the invention shown in Figs. 8 and 9 of the drawings, as well as in that form shown in Figs. 10 and 11, the buttons when overlying the upper surfaces of the individual holders or carriers prevent the trays from dropping away from the holders or carriers when the bottles are positioned to be supported by a table or the like.

Having fully described my invention what I claim as new and desire to secure by Letters Patent is:

1. A bottle holder and carrier including a stationary member, a movable member connected thereto, the movable member being adapted for movement into position to permit the reception of the neck of a bottle between the members and then positioned for cooperation with the stationary member to support the bottle therefrom, and a member carried by the movable member and engageable with the stationary member for preventing spreading of the members from bottle-supporting position.

2. A bottle holder and carrier including a stationary member having longitudinally spaced recesses in one edge, cleats secured to the underside of the stationary member and having portions projecting laterally from that longitudinal edge of the stationary member having the recesses therein, and a movable member connected to the ends of the laterally extending portions of the cleats for swinging movement relative to the stationary member and into bottle receiving or bottle supporting position, said movable member having longitudinally spaced recesses cooperating with the recesses in the stationary member to provide circular openings to receive the necks of the bottles and the movable member being supported on the upper surfaces of the laterally extending portions of the cleats and on the same plane as the stationary member when in bottle supporting position.
